UNITED STATES PATENT OFFICE.

RODNEY S. PULLEN, OF ATLANTIC CITY, NEW JERSEY, ASSIGNOR TO PULLENLITE COMPANY, OF PHILADELPHIA, PENNSYLVANIA, A CORPORATION OF PENNSYLVANIA.

MATCH BOOK.

Application filed April 23, 1927. Serial No. 186,097.

My invention has for one of its objects the construction of a match book or package wherein a plurality of matches are detachably held in definite correlation within a suitable holder wherein they are supported and properly guided when being withdrawn, the holder being so formed that it acts as a protection to the matches and, at the same time, causes them to be ignited during the 10 act of separately withdrawing the matches from the holder.

A further object of my invention is to so form the holder that separate compartments are respectively provided for normally 15 shielding the heads of the matches and for the means for igniting the said heads when being withdrawn, and whereby the flame of ignition is prevented from reaching the heads of the remaining matches and, preferably, from escaping in any manner where 20 it might injure the hand of the user of the match book.

A still further object of my invention is to so construct the holder for supporting and 25 guiding the match sticks that a temporary resistance is provided to prevent free withdrawal of the matches and which, in being overcome, causes the match to be so released that the head thereof is drawn quickly in 30 contact with the igniting means and thence out of the holder in a lighted condition, said quick action thus inducing and insuring a greater friction with the igniting material and hence a positive lighting of the match.

My invention has for a further object the 35 forming of the holder of sheet material so shaped and assembled as not only to provide proper shielding and guiding of the match with sufficient exposure of the match sticks 40 for gripping them in the act of withdrawal, but also to so shape the outer surfaces of the holder as to provide suitable parts upon which printing may be readily placed for advertising or other purposes.

With the above and other objects in view, 45 the nature of which will be more fully understood from the description, the invention consists in the novel construction of match book, as hereinafter more fully described and 50 defined in the claims.

Referring to the drawings: Fig. 1 is a 55 perspective view of a match book embodying my invention; Fig. 2 is a transverse section of the same taken on line 2—2; Fig. 3 is a plan view of a cardboard strip scored and

perforated and also provided with the igniting material before being folded into condition in the complete book form; Fig. 4 is a plan view of the same with a portion thereof folded over and ready to be clamped for retaining the form shown; Fig. 5 is a plan view of the strips folded further upon itself and with the match sticks thrust through the guiding means of the strip; Fig. 6 is a similar view of the strip when it has received the 65 final fold and the clamping means have been clinched to provide the complete match book of the form shown in Fig. 1; Figs 7 and 8 are perspective views of the metallic clamping means for holding the strip in folded 70 condition, and in the latter case being bowed for applying a spring pressure upon the match sticks; Fig. 9 is a cross sectional view similar to Fig. 2, but with use of the curved bow of Fig. 8 instead of the straight bow of 75 Fig. 7; and Fig. 10 is a side view of my improved match book when made double.

2 is a strip of cardboard which is transversely scored at numerous places such, for example, as at 12, 15, 19 and 22, said scoring 80 being duplicated to provide respectively narrow strip portions 4, 5, 7 and 23 which constitute the spacing portions between the broader flat side portions and whereby the completed structure is provided with compartments, as will be presently described.

The parallel scored portions 12 are at a distance from one end of the strip to provide a large end surface 11 of rectangular form and which is preferably further scored along 90 lines 14 near each of the lateral side edges of the strip to form flaps 14 which are free to be bent at right angles to the plane of the surface 11 by reason of the fact that short cuts 13 are formed at the ends of the flaps 95 adjacent to the scoring 12 to permit the flaps to be freely bent upward from the main surface 11, as seen in Figs. 1, 2, 4 and 9.

The narrow strip portion 4 between the scored lines 12, 12, is provided with a series of holes 7 which may be more or less counter-sunk or weakened to give yielding annular edges, or petticoats so that when a match stick is pushed through the holes the head fits snugly in position next to the 105 hole and the hole makes a relatively close fit around the match stick to prevent accidental ignition when another match is being ignited, as explained hereinafter. Furthermore, these holes 7 are such that they form 110

an obstruction or resistance to ready passage of the match head through them, so that when the match is forcibly pulled to draw the head through said apertures, the 5 same is suddenly released when passing through the hole and thereby provides a quick movement to the match when so released.

The narrow strip 5 formed between the 10 transverse scoring 15, 15, and parallel to the transverse strip 4 is spaced from the latter by a portion of the card strip 2 shown at 16 and nearly equal in size to the surface 11, and said strip 5 is provided with a row of 15 apertures 6 corresponding in number to the apertures 7 of the strip 4 but of larger area, so that not only the match sticks but the heads thereof when ignited may be readily drawn through and released without snuffing out the flame.

Furthermore, the surface 16 is provided with a match igniting material 18 arranged transversely along its surface adjacent to the apertured strip 5; and similarly, the surface 25 face 11 is provided with a match igniting material 17 arranged at the extreme end of the cardboard strip 2 so that when the part 11 is folded over, parallel to the part 16 and spaced therefrom by the perforated strip 4 and the flaps 14^a, the two layers of igniting material 17 and 18 are brought into opposed relation so that when the match heads are drawn between them, ignition of the match head is doubly assured. It will be understood, however, that one of these 35 layers of material might be omitted, if so desired.

When the part 11 is folded over above the part 16, as above described, and before the matches are inserted, the parts will bear the relation shown in Fig. 4, and at this stage the clamping strip 27 is placed over the part 11 and holds the flaps 14^a in their transverse position. When the parts are so formed, the strip portions 11 and 16 provide a box-like chamber or compartment 3 having its bottom formed by the perforated strip portion 4. This box-like construction is then folded over upon the strip portion 20, the same coming in direct contact with the portion 11, and what was the open end of the box-like compartment 3 is closed by the perforated transverse strip portion 5.

The match sticks 9 are thrust through the 55 holes 7 and larger holes 6 and with the heads 10 close to the said hole 7 of the transverse strip 4, said parts then being in the relation shown in Fig. 5. From this figure, it will be observed that the length of the strip 16 (in 60 the direction of the length of the match sticks) is less than the length of the part 20, so that the scored portions 19 and transverse strip 7 provide an outer bottom when the parts 16 and 20, with the matches in position, are turned over upon the part 21 of

the card strip, as shown in Fig. 6. This will provide the compartment 8 in which the match heads 10 are located and by which they are shielded, said compartment being clearly indicated in Figs. 1 and 10.

The length of the portion 21 is so much greater than the portion 20 that part of 21 projects and provides a wall in front of which the match sticks 9 are arranged, as clearly shown in the drawing. When the strip 2 has been folded in this manner, the portion 16 will be resting upon the portion 21, as indicated in Figs. 1 and 2, and these are positively attached to each other by means of the flanges 28 of the metal strip 27 which are bent over and clinched as at 29. These flanges are clinched at each end of the metallic strip and thus holds the folded strip 2 with the various parts in the relation described. Moreover, the metallic clamping of the parts together in this way obviates the use of glue or adhesives which are affected by climatic conditions and are, therefore, objectionable.

As shown, the cardboard strip 2 is still further extended by the narrow transverse portion 23 positioned by the scoring 22, 22, and also by the flap portion 24 beyond the said scoring 22, whereby these parts 23 and 24 may be turned over and employed as a closure over the match sticks, as will be readily understood from Fig. 1. The flap 24 is preferably provided with a tongue 25 which may be thrust into a slit 26 formed in the wall surface 20. It will be understood, however, that the flap 24 and the transverse portion 23 (constituting a hinge therefor) may be entirely omitted, if so desired.

The metal clamping strip 27 definitely holds the part 11 or inner wall of compartment 3 in position in respect to the opposite walls 16 and 21; and its end portions 27^a hold the flaps 14^a in position between the wall portions 11 and 16 so that they assure closed side portions to the compartment. Furthermore, the ends 28 being bent around the side edges of the parts 16 and 21, bind them firmly together. The end flaps 14^a and the transverse portions 7 and 4, between scorings 19, 19 and 21, 21, respectively, give rigidity to the structure, preventing the outer edges of parts 11, 16, 20 and 21 being crushed in by handling or packing. The side closure flaps 14^a insure a comparatively closed compartment 3 for the match igniting materials 17 and 18, and shield the same against deterioration from atmospheric conditions and, as before indicated, prevent outbursts of flame due to ignition.

The igniting material 17 and 18 is preferably near the upper portion of the walls of the compartment 3 and hence farthest removed from the compartment 8 in which the match heads 10 are confined. They are also separated from the head compartment

by the bottom wall 4, by reason of which the match heads within the compartment 8 are secure against accidental ignition when a match is being withdrawn and ignited.

- 5 By having the two series of spaced holes 6 and 7 in the transverse bottom and top portions 4 and 5, the matches are normally held out of contact with each other and are guided when being withdrawn. By having 10 the apertures 6 large enough to permit free passage of the ignited match heads 10, there is no resistance to a very quick continued movement past the igniting areas 17 and 18 and out from the compartment and consequently no danger of spreading the flame.

The upper and lower series of holes 6 and 7 are sufficiently spaced between the side walls 11 and 16 of the folded case or container to insure adequate space for the match sticks and prevent them from rubbing off the igniting material 17 and 18 while the matches are being withdrawn or when the match book is carried in the pocket. Each match has, as it were, its own individual igniting surface and such surface is concealed and protected from abrasion or disturbance during storage, handling or use.

I prefer that the metallic clamping strip 27 shall be slightly curved or bowed, as shown in Figs. 8 and 9; and that, when in position upon the inner wall portion 11, it shall cause a slight even spring tension to be given across the entire width of the same and in substantial alinement with the layers of igniting materials 17 and 18. By reason of the spring tension thus provided, the matches are individually caused to become ignited on being withdrawn, even though the sizes of their heads 10 vary in bulk to a considerable extent; and by the use of the bowed strip 27, the necessity of applying pressure by the fingers upon the package to insure ignition of the matches, when being withdrawn, is overcome. The use of the metal strip 27 keeps the case or holder in shape, preventing warping or distortion from climatic conditions or by carrying the match book in the pocket.

When withdrawing a match there should be no undue friction to the same after the head thereof has been pulled through the apertures 7, and if it were not for the spacing flaps 14^a and metal strip 27, the walls 11 and 12 would crush down at their sides and bind upon the outermost matches of the series and crowd them out of their intended alinement during withdrawal and inviting liability of failure to ignite.

I have described my invention in respect to a match book providing a single row of matches, but it is manifest that more than one row of matches may be provided by duplicating the structure described, as indicated in Fig. 10, wherein one of said single row match books is shown, as it were,

formed on the flap 24 of Fig. 1. I do not restrict myself as to the manner in which such duplication may be effected.

It will now be apparent that I have devised a novel and useful construction which embodies the features of advantage enumerated as desirable; and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim and desire to secure by Letters Patent is:

1. A match book or package comprising a long card strip folded upon itself transversely at a plurality of spaced positions and the folds respectively in substantially parallel arrangement and forming a box-like structure having two compartments separated by a transverse perforated wall in the bend of one of the folds and held in folded condition, combined with a plurality of match sticks having their body portions extending through one of the compartments and the perforated wall with their heads arranged in the other compartment below the perforated wall and frictionally held therein.

2. The invention according to claim 1, wherein further, the box-like structure provides a second transverse perforated wall through which the match stick bodies extend and by which they are held in spaced alinement, and means for igniting the matches located intermediate of the perforated wall portions and against which the match head is drawn into contact for igniting the matches as the matches are withdrawn.

3. The invention according to claim 1, wherein further, end flaps are provided, bent inwardly to close the ends of the compartment interposed between the perforated walls and to cause the side walls of the box-like structure to be held in definite spaced relation and to prevent crushing in the package.

4. The invention according to claim 1, wherein further, the box-like structure provides a second transverse perforated wall through which the match stick bodies extend, held in spaced relation to the first and wherein the inner wall intermediate of the two perforated walls is provided with a transverse layer of igniting material with which the heads of the matches make contact when the matches are being withdrawn, and wherein also a metallic bow is provided extending transversely across one of the walls of the box-like structure parallel to the layer of igniting material, having its end

bent around the side edges of the folded card walls to clip them in permanent relation.

5. The invention according to claim 1, wherein further, the box-like structure provides a second transverse perforated wall in one of the bends of the fold, through which the match stick bodies extend and by which they are held in spaced alinement, and 10 wherein also the end of the card strip is extended beyond the box-like structure and its second transverse perforated wall to protect the protruding match stick ends.

6. The invention according to claim 1, 15 wherein further, end flaps are provided and are bent inwardly to close the ends of the compartment interposed between the perforated walls to cause the side walls of the box-like structure to be held in definite 20 spaced relation and to prevent crushing in the package, and in which also the end flaps and edge of wall intermediate of its flaps act as a supporting abutment within the box-like body to sustain the perforated wall 25 when the match heads are forcibly drawn through it.

7. A match book or package, comprising a box-like structure having two compartments one above the other in the same plane 30 and separated by a perforated wall and having an opposed wall of one of the compartments also perforated, combined with matches having their body portions extending through both perforated walls and the 35 intermediate compartment and their head portions arranged within the other compartment and igniting means located between the two perforated walls.

8. A match book cover comprising a single 40 strip of material extending along the length of the matches, reversely turned about the heads of the matches following the greater part of the length of the matches toward the stick ends of the matches, and reversely 45 turned and apertured in the turned portion to hold matches separated at this point, extending toward the head of the match to form a second protecting wall along the back of the package, and transversely turned and apertured close to the heads of the matches to form with the first turn a compartment for the heads of the matches and so as to extend toward the stick ends of the matches to form a second wall protecting the fronts of the 55 matches.

9. A match book cover comprising a single strip of material extending along the lengths 60 of the matches, reversely turned about the heads of the matches, following the greater part of the lengths of the matches toward the stick ends of the matches, reversely turned and apertured to hold the matches separated at this point, extending toward the heads of the matches to form a second protecting wall along the back of the package 65

and transversely turned and apertured close to the heads of the matches to form with the first turn a compartment for the heads of the matches and so as to extend toward the stick ends of the matches to form a second 70 wall for the fronts of the matches, the sides of one of the inner walls extending lengthwise of the matches being turned transversely to form a partial closure for the sides of the match compartment formed. 75

10. A match book having double walls throughout the greater part of the length of the match stick, with transverse connecting walls across the matches close in front of and close back of the heads of the matches 80 to form a compartment for the match heads and having petticoated apertures in the latter of these connecting walls to close off the heads of the matches from the compartment and friction material in the paths of the 85 matches as they are withdrawn from the compartment whereby the petticoating protects during the withdrawal of the match.

11. In a match book, integral walls forming a striking compartment and a compartment for the heads of the matches, the walls being apertured to provide individual positions for the matches and the apertures nearest to the heads of the matches being petticoated to protect the head compartment from 90 flame from the striking compartment and to give friction to the matches so as to increase the speed of passage of their heads through the striking compartment. 95

12. In a match book, walls reversely bent 100 to form a head compartment and a striking compartment separated by a perforated wall, a second perforated wall at the opposite end of the striking compartment and double walls front and back in the striking compartment, friction producing material upon the interior of the striking compartment and side flaps for the striking compartment integral with one of the double walls of the 105 compartment. 110

13. A match package comprising a match head compartment and a striking compartment terminated endwise by transverse walls, the wall between the compartments near the match heads being apertured to space the 115 matches and to retard passage of the heads, friction producing material between the limiting walls at the ends of the striking compartment and spring-pressure means for forcing the front and back of the striking 120 compartment toward each other throughout the entire package width to ensure striking of the match heads.

14. A match package, comprising a match head compartment and an immediately adjoining striking compartment terminated endwise by transverse walls, the wall between the compartments near the match heads being apertured to space the matches and to retard 125 passage of the heads, friction producing ma- 130

terial within the striking compartment and spring pressure means anchored at the sides of the compartment for forcing the front and back of the striking compartment toward each other throughout the entire package width to ensure striking of the match heads.

15. A match package having positioning means for the matches and a striking compartment, friction producing material in the striking compartment about the match sticks, an end wall of the striking compartment being adapted to protect the heads of the remaining matches against flash from the striking compartment and to retard the matches until the heads enter the friction compartment and a spring clamp pressing against the cover about the matches to ensure frictional striking pressure as the match heads pass through the striking compartment.

20 16. A match package, a strip of material bent upon itself to form a compartment for the heads of the matches and a striking compartment, normally covering the greater part of the lengths of the sticks of the matches and apertured at the ends to separately hold the matches, a striking material in the striking compartment and a metallic spring holder adapted to bring lateral pressure there upon the matches throughout the width of the package, anchored at the sides of the package and there holding the walls of the package together.

25 17. In a book match package, a strip bent upon itself to form a striking compartment apertured at the ends to individually retain the matches, and a spring pressure clip adapted to bring pressure to bear laterally across one side of the striking compartment, the side walls of the compartment being bent down to close the sides of the striking compartment and held in bent position by the clip.

30 18. A book match package comprising a single strip reversely bent to form a compartment for the heads of the matches and an adjoining compartment containing strik-

ing material but normally occupied by the sticks of the matches, the ends of the striking compartment being apertured to position individual matches and at the head ends protecting the heads of the matches and the strip being bent down at the sides to close the sides of the striking compartment, and a spring metal strip pressing the walls of the compartment in a direction across the compartment at one side, retaining the edges of the bent strip in position by the ends of the clip and secured to the casing at opposite sides of the compartment to hold the package together.

35 19. A match package comprising a cover reversely bent to form a match body compartment and a head compartment having a plurality of matches therein, striking material inside the body compartment and a spring clip anchored at the edges of the body compartment and spring pressing the back of the body compartment toward the front of the body compartment to ensure engagement of the match heads with the striking material.

40 20. A match package cover, and a holder for the matches therein retaining them by friction against the heads and petticoated about the individual match sticks.

45 21. A match package comprising side walls and transverse walls forming a head compartment and a striking compartment containing striking material adjacent to the match sticks and in which the matches are spaced within apertures in the walls at the two ends of the striking compartment, the apertures at the head end of the compartment being a relatively tight fit upon the matches to retard the movement of the match heads and the apertures at the opposite end of the striking compartment being large enough to pass the match heads without objectionable retardation.

50 55 60 In testimony of which invention, I hereunto set my hand.

RODNEY S. PULLEN.
